UNITED STATES PATENT OFFICE.

BENJAMIN WALKER PETERSON AND JOHN WILSON CONNELLY, OF WHEELING, WEST VIRGINIA.

MORTISING-CHISEL.

SPECIFICATION forming part of Letters Patent No. 339,806, dated April 13, 1886.

Application filed August 5, 1885. Serial No. 173,610. (No model.)

To all whom it may concern:

Be it known that we, BENJAMIN WALKER PETERSON and JOHN WILSON CONNELLY, citizens of the United States, residing at Wheeling, in the county of Ohio and State of West Virginia, have invented certain new and useful Improvements in Cutting Attachments for Mortising-Machines; and we hereby declare the following to be a full, clear, and exact description of the same, reference being had to the accompanying drawings, in which—

Figure 1 is a perspective view of the bit or chisel of a mortising-machine provided with our improved gain-cutting attachments. Fig. 2 is a side elevation, and Fig. 3 an end elevation, of the same. Figs. 4, 5, and 6 are detached views of the bits or chisels peculiar to the attachment. Fig. 7 is a view of a portion of a box window-frame pulley-stile, showing the work of the cutting attachment. Fig. 8 is a view showing the operation of the tool, the full line showing its first direction and the dotted lines its reversal.

Like letters refer to like parts wherever they occur.

The object of the present invention is to provide cutting attachments for the bits of the ordinary vertical mortising-machines employed in mortising the pulley-stiles of window-frames, the lock-stile of doors, and like places where it is necessary or desirable to surround the mortise with a gain or housing for receiving the flange of a lock, pulley-box, or like article; and it consists, generally stated, in a clamping-stock adjustable on the bit of the mortising-machine, and provided with a forward or leading bit and an intermediate bit, the whole adjustable on the bit of the mortising-machine, so as to cut a housing or gain of any required length, width, or depth simultaneously with the cutting of the mortise and with a single reversal of the tool.

Heretofore, so far as we are aware, all attachments for a like purpose have demanded a special construction of the main bit or chisel of the mortising-machine, and have either left a portion of the gain to be cut by the ordinary hand-tool or necessitated the unnecessary enlargement or lengthening of the mortise and several reversals of the tool to avoid the neces-

sity of hand-finishing the gain. Our devices are simple, efficient, avoid these several objections, and are adapted for use with the bit of the character commonly used in mortising-machines.

We will now proceed to describe our invention more specifically, so that others skilled in the art to which it appertains may apply the same.

In the drawings, A indicates the ordinary cutting-bit used in mortising-machines.

B is the improved stock or attachment which carries the gain-bit. This stock B has a slot, b, through which passes the bit A, so that the stock is vertically adjustable on the bit, and can be raised or lowered to vary the depth of the housing or gain to be cut.

E indicates a clamp-screw for securing the stock B.

The forward end or beak of stock B is recessed, as at c, to form a seat for the forward or leading bit, and is also recessed within the slot b, as at c, to form a seat for the intermediate bit.

A clamp-screw, F, is used for holding the leading or forward bit, while the intermediate bit is held by being clamped between the stock B and the bit A of the mortising-machine.

G indicates the forward bit, which is provided with a hole, g, for the passage of clamp-screw F, and D indicates the intermediate bit, which is preferably cut out, as at d, so as to straddle the mortise. As a preferred construction, both bits G and D are formed with shoulders e, or, in other words, are wider than the slots in the stock B, so as to bear firmly on and be held steady by the stock.

In securing these devices to the ordinary mortising-machine the stock B is slipped on the bit A, and adjusted to the proper height thereon to give the desired depth of gain, the intermediate bit, D, is inserted between the stock B and bit A, and the set-screw E is tightened to secure the parts. The forward or leading bit, G, is then secured by its clamp-screw F. The cutting-edges of bits D and G must be set even; but they can be adjusted so as to cut gains H any required depth or width.

H indicates the gain when cut, and I the mortise.

The devices will operate as follows: In Fig. 8 the full lines represent the initial positions of the mortising-tool and the cutting attachments, as well as the successive steps as it sinks deeper in the wood and advances. When the mortising-chisel A gets its full depth, the two auxiliary chisels or bits G D begin cutting at the points shown by the lines *x x* and *y y*, and as the chisels advance, the chisel D cuts out all the space of the shallow mortise from *x* to *y*, (which in the devices heretofore devised would not be touched,) so that when the tool is reversed the intermediate bit or chisel, D, will, as shown in dotted line, set back 15 of the gain cut or line *x*, and as it advances will commence at the line *x* or edge of the uncut portion. It will thus be seen that a single reversal of the tool will cut the housing or gain completely, which cannot be done by any 20 other attachment now known or employed for cutting housings or gains.

We are aware that prior to our invention an auxiliary gain-cutting chisel has been combined with a mortising-chisel, and do not, 25 therefore, broadly claim such a combination; but,

Having thus described the nature and operation of our invention, what we claim, and desire to secure by Letters Patent, is—

30 1. In a gain-cutting attachment for mortising-machines, the combination, with a bit-stock which is adjustable on the main or slotting bit of the machine, of a leading or gain bit and an intermediate bit adjacent to the main

bit, substantially as and for the purposes specified. 35

2. In a gain-cutting attachment for mortising-machines, a bit-stock having a slot and clamp-screw for securing the stock to the main bit of the mortising-machine, and provided 40 with a recess or bit-seat for the reception of an auxiliary or intermediate bit, which is clamped between the bit-stock and bit of the mortising-machine, substantially as and for the purposes specified. 45

3. In a gain-cutting attachment for mortising-machines, the combination, with a slotted bit-stock which is vertically adjustable on the main or slotting bit of the machine, of a shouledered leading or gain bit, G, substantially as 50 and for the purposes specified.

4. In a gain-cutting attachment for mortising-machines, a leading-bit and an intermediate straddle-bit, in combination with an adjustable bit-stock provided with clamp-screws, 55 (the straddle-bit being clamped between the bit-stock and the main or slotting bit of the machine,) substantially as and for the purposes specified.

In testimony whereof we affix our signatures, 60 in presence of two witnesses, this 10th day of July, 1885.

BENJAMIN WALKER PETERSON.
JOHN WILSON CONNELLY.
